UNITED STATES PATENT OFFICE.

LORA B. HOIT, OF WORCESTER, MASSACHUSETTS.

WAGON OR LIFTING JACK.

SPECIFICATION forming part of Letters Patent No. 251,882, dated January 3, 1882.

Application filed November 21, 1881. (No model.)

To all whom it may concern:

Be it known that I, LORA B. HOIT, a citizen of the United States, residing at Worcester, in the county of Worcester and State of Massachusetts, have invented certain new and useful Improvements in Wagon or Lifting Jacks, of which the following is a specification, reference being had therein to the accompanying drawings.

10 The invention is designed more particularly to increase the strength of such implements, as also to add to their general utility.

Figure 1 is a perspective view of the invention, showing it in the position which it occupies when in use to support a wagon-axle or other object. Fig. 2 shows, on enlarged scale, a detail of the invention. Fig. 3 indicates a modification in the construction of the standard.

20 Similar letters of reference indicate similar parts in the respective figures.

A is the base which supports the standard B, made of hard wood. The standard is tenoned, and is held in the mortise of the base by 25 a pin, a. The standard B is wider at its lower than at its upper end, in order to give increased strength where most required. The front edge of the standard, from a point about central of its height down toward the base, is provided 30 with notches a', opening downward at an angle, as shown, and the upper part of said edge is guarded or strengthened by an iron re-enforcing strap, C, which is riveted or bolted to the standard, as represented. The upper portion 35 of the rear edge of the standard is also provided with larger notches, c, which open upward at an angle, as shown. The material about the lower portion of these notches is strengthened by rivets d, which are passed 40 through the standard and riveted over in countersunk holes formed in the face of the bar or plate C.

D is a lever, which is longitudinally slotted at b, so as to adapt it to fit over the standard 45 in the manner shown. Each side of the forward end of said lever is preferably strengthened by a metallic plate, f, the plates being riveted to the lever and to each other by rivets g. The central rivet, g, constitutes the fulcrum of the lever, and is adapted to rest in any

of the notches c. The outer end of the lever is provided at its top with a plate, H, which curves upwardly at its extremity, forming a lip, h. The plate H is slotted to clear the standard, and serves as a guard to each side of the 55 slot in the lever.

E is a shackle or link, which is loosely hung to the top of the lever D, and held thereto by a plate or cap, i, riveted to the lever. The forward or lower end of the shackle or link is fitted to enter any of the notches a' at the front edge of the standard.

In operation, when by pressing on the lever the wagon is raised to the proper height, the shackle or link E drops into one of the notches 65 a', the weight of the wagon upon the outer extremity of the lever drawing the shackle or link against the standard and not directly upon the material surrounding the notches a'. The fulcrum-pin d resting in one of the notches c 70 at the rear edge of the standard, the weight of the wagon or object sustained, were not precautions taken against such a result, might tend to fracture the material of the standard at that point. To avoid this the rivets d are employed, upon which the weight is very largely brought. The plate H, at the outer extremity of the lever, by its lip h, prevents the axle or other object from slipping from the lever. The strap C, in addition to strengthening the standard, also serves to protect the front edge of the standard from becoming bruised or worn by the contact of the axle or other object raised. When the work—such as greasing the axle—is done and the wheel is to be let down, the lever must be depressed, so as to remove the strain from the shackle or link. It must then be pushed out of the notch, when the short end or arm of the lever sustaining the axle can be allowed to fall gradually.

90 The notches a' and c should be about two inches apart, so as to give an easy pitch to the lever and to suit all heights of carriages.

Fig. 3 shows a modification in the construction of the standard, consisting of a notched plate formed of malleable iron or other suitable metal, inserted in the rear edge of the standard, which, together with the strengthening plate at the forward edge and the rivets, gives great strength to the upper portion of the stand- 95 100

ard. This modification is not claimed by me as a part of the invention, as I am aware that similar plates have been heretofore employed. The material surrounding the notches on the front edge of the standard not receiving the strain directly, means for strengthening them are not so necessary; but, if desired, they may be formed in a plate inserted in the same manner as the plate above described.

10 My improvements insure strength, cheapness, utility, and simplicity in the manufacture and use of the implement.

I claim as my invention—

15 In a wagon or lifting jack, a standard provided at its front edge with a re-enforcing strap and with notches opening downward, and at

its rear edge with notches opening upward, the material about the latter being strengthened by rivets passed through the standard and strap, as described, combined with a slotted 20 lever having a fulcrum adapted to rest in one of the notches at the rear edge of the standard, and with a loosely-hung shackle or link fitted to enter any of the notches at the front edge of the standard, substantially as specified.

In testimony whereof I affix my signature in presence of two witnesses.

LORA B. HOIT.
